(57) **CLAIM**

I claim the ornamental design for a power shovel bucket body, as shown and described.

DESCRIPTION

FIG. 1 is an upper perspective view of an embodiment of my power shovel bucket body;

FIG. 2 is a lower perspective view of the power shovel bucket body shown in FIG. 1;

FIG. 3 is a left side view of the power shovel bucket body shown in FIG. 1;

FIG. 4 is a right side view of the power shovel bucket body shown in FIG. 1;

FIG. 5 is a top plan view of the power shovel bucket body shown in FIG. 1;

FIG. 6 is a bottom plan view of the power shovel bucket body shown in FIG. 1;

FIG. 7 is a front side view of the power shovel bucket body shown in FIG. 1; and,

FIG. 8 is a rear side view of the power shovel bucket body shown in FIG. 1.

The dashed lines in the figures represent environment and form no part of the claimed design.
